CHIMNEY CLEANER

William M. Anderson, Downing, Wis.

Application March 25, 1941, Serial No. 385,184

4 Claims. (Cl. 15—242)

This invention relates to a tool designed primarily for cleaning chimneys.

Heretofore difficulty has been experienced in cleaning out the angular corner portions of a chimney and, in order to properly clean the surfaces it has been necessary usually to use different tools.

An object of the present invention is to combine in a single tool a cleaner designed for scraping both curved and angular surfaces, it being possible readily to adjust the tool for either purpose.

A further object is to provide a tool which can be detachably secured to a long handle, such as a fishing pole, and thus operated in a chimney of considerable length.

A still further object is to provide a cleaner which is simple in construction and can be used readily.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawing the preferred form of the invention has been shown.

In said drawing

Figure 1 is a front elevation of the tool adjusted for use in cleaning out the corner portions of an angular chimney flue.

Figure 2 is a top plan view thereof.

Figure 3 is a section on line 3—3, Figure 1.

Figure 4 is a side elevation.

Figure 5 is a view similar to Figure 1, showing the tool adjusted for use in scraping the curved wall of a chimney flue.

Figure 6 is a plan view of a blank from which the blades are formed.

Referring to the figures by characters of reference, A designates a blank forming a substantially semicircular blade 1 from the straight side of which is extended an angular blade 2. This blank is adapted to be folded along the line 3 and it has a central slot 4 extending into both blades. Furthermore located in each of the blades and adjacent to the respective ends of the slot are separate pairs of bolt holes 5 and 6 respectively.

As before stated the blank, which can be made of any durable material, such as sheet steel, is folded along the line 3 so that the two blades will be positioned at right angles to each other.

The slot 4 is of such size that when the blank is folded, one end portion of an elongated handle 7 can be seated in that end portion of the slot located within the uppermost blade. For example, if the angular blade is uppermost, as shown in Figures 1, 2 and 3, the end portion 7 of the handle will extend into that end portion of the slot 4 projecting into the angular blade 2.

The handle is secured to the blades by placing 10 a U-bolt 8 astride the handle and inserting the threaded terminals thereof through the openings 5 in the semicircular blade 1. The threaded terminals of the bolt can also be extended through a plate 9 which acts to clamp upon the elongated 15 looped ends 10 of a resilient loop 11 constituting a ring-like gauge. This loop can be made of steel or other suitable material and obviously by placing nuts 12 on the ends of the U-bolt 8 and tightening them, all of the parts can be held together securely.

With the parts assembled as shown in Figures 1 to 3 inclusive, the tool can be lowered into a chimney flue and the angular blade used for scraping the flat walls of the flue and up into the corners thereof. The gauge ring 11 serves to hold the blade 2 pressed yieldingly against the surfaces of the flue and it also acts to guide the tool in the flue. By loosening plate 9 the loop can be made larger or smaller to adapt the 30 tool to flues of different sizes.

If the flue is not angular but is round, the handle is detached, the blade 1 brought uppermost, and the handle then inserted into that portion of the slot 4 extending into the blade 1. 35 The handle is then fastened to the blade 2 by inserting the U-bolt into the opening 6 after it has been placed astride the handle. It is also attached to the plate 9 so that the resilient loop 11 will thus be extended outwardly from the 40 blade 2 as shown particularly in Figure 5. Thus the tool can be used for scraping curved flue surfaces in the same manner as heretofore explained.

What is claimed is:

- 45 1. A cleaning tool for chimney flues and the like including a handle, a scraping blade, means for holding the scraping blade fixedly at an angle to one end portion of the handle, a resilient ring-like gage having oppositely extended terminal loops, and means for holding the loops fixedly relative to each other and the handle, each of said loops being adjustable relative to its holding means.
- 50 2. A cleaning tool for chimney flues and the like including a handle, a scraping blade having

a portion extended along the handle, said blade being positioned at an angle to the handle, a resilient ring-like gage having oppositely extended terminal loops, and means engaging said loops and a portion of the blade for securing the loops adjustably to the handle and attaching the blade to said handle.

3. A cleaning tool for chimney flues and the like including a handle, a scraping blade carried thereby and extended at an angle therefrom, an expandable and contractable ring-like gage, and means for adjustably connecting said gage to the handle and blade.

4. A cleaning tool for chimney flues and the like including a handle, a scraping blade carried thereby and extended at an angle therefrom, an expandable and contractable ring-like gage, and means for adjustably connecting said gage to the handle and blade, said means including a bolt extended through the loops and means on the bolt for clamping the loops against a portion of the blade, said loops, when relieved from pressure, being shiftable longitudinally relative to their clamping means.

WILLIAM M. ANDERSON.
